CLAIM

The ornamental design for a combined beach chair and backrack, as shown and described.

DESCRIPTION

FIG. 1 is a side elevational view of a combined beach chair and backrack showing my new design with the opposite being a mirror image;

FIG. 2 is a front elevational view thereof, taken in the direction of the arrows on line 2—2 of FIG. 1;

FIG. 3 is a rear elevational view thereof;

FIG. 4 is a top plan view thereof;

FIG. 5 is a bottom view thereof; and,

FIG. 6 is a front perspective view thereof.

FIG. 6 has been shown on a reduced scale and the strap members have not been shown for ease of illustration.
